UNITED STATES PATENT OFFICE

EDWARD J. NEWBAKER, OF WINDBER, PENNSYLVANIA, ASSIGNOR TO THE BERWIND-
WHITE COAL MINING COMPANY, A CORPORATION OF PENNSYLVANIA

MINING APPARATUS

Application filed January 3, 1930. Serial No. 418,177.

My invention relates to the mining of mineral substances and is particularly adapted to mining coal of various kinds such as bituminous, semi-bituminous, anthracitic, anthracite or other kinds which are preferably more or less cleavable so that they may be separated from the mass in situ, but by means of my method of operation and apparatus I can also mine more dense, massive and strong minerals. 5 My invention uses a tool which is powerfully operated and which can also accomplish this, as to mine such massive or strong minerals only requires more time and energy as compared with those of a more cleavable and friable nature.

In order however to simplify the descriptions herein I will confine these to the mining of coal so as to more briefly and concisely describe my invention.

20 My apparatus, comprising the combination of a pickhammer and a tool with an inclined point portion is very light and easily handled or manipulated into any position by a single miner and, for certain purposes is therefore adaptable without other supports to make a cut in any location or position, and with it the miner can also cut the coal of pillars which are under a greater pressure than the main seam, as such pressure facilitates the 25 removal of the coal for the reason that the pressures existing in the pillars, due to the greater intensity of load which they carry by reason of the superincumbent material thereon, causes them to be more readily cut, sheared or shattered, and in some cases such pillars 30 can be removed by cutting their exposed faces at various locations without the necessity of blasting as compared with cutting the main coal seam as elsewhere described and illustrated herein and then blasting it.

35 However in order to minimize the amount of labor and effort on the part of the miner when making the customary undercut in the coal seam prior to blasting, I mount my pickhammer and tool on a very light carriage comprising a pair of wheels which are supported on the floor of the mine and which are provided with an axle with a frame thereon carrying a socket into which the pickhammer 40 can be inserted or withdrawn and within

which it can be rotated as desired by the miner when grasping the handles thereof and the frame is so arranged on the axle that it can be swung backward or forward so that the tool may be presented in any position or 45 at any angle desired to the working face of the coal.

By reason of its light and easily manipulated construction such a tool can be operated in difficult positions, can accommodate 50 itself to irregularities in the coal seam, can pass over what are known as rolls or projections in the bottom or elsewhere, can be operated to avoid hard portions of bone coal, nigger heads or sulphur balls and this 55 cannot be accomplished by the other and more unwieldy and heavier types of machines previously referred to herein.

By reason of the wheel support my apparatus may be also traversed along the 60 length of the working face and moved backward or forward as desired. In this respect its operation is universal in its adaptation and suited to all purposes and conditions of its intended use.

Having thus given a general description of my invention I will now, in order to make the matter more clear, refer to the accompanying 65 two sheets of drawings forming part of this specification and in which like characters of reference refer to like parts:—

Fig. 1 is a vertical sectional elevation through a coal seam and the floor and roof thereof showing a side view of my apparatus in place.

Fig. 2 is an approximately horizontal sectional view of a coal seam with the forward end of my tool shown in elevation indicating the manner of beginning the undercut.

Fig. 3 is a rear view of the truck or wheeled support of my apparatus.

Fig. 4 is a side view or elevation of the same showing also the apparatus mounted thereon with a portion of the tool projecting 85 outwardly, the forward end of the tool being broken away to provide clearness of illustration.

Fig. 5 is a front view of the axle and frame part of my wheeled support showing the 90

socket in its closed position in full lines and in its open position in dotted lines.

Fig. 6 is a side elevation of that part of the construction shown in Fig. 5, and Fig. 7 is a side elevation of one of the wheels. Fig. 8 is a top plan view of the frame and axle of my machine corresponding to the elevations of Figs. 5 and 6; Fig. 9 is a cross section of one of the wheels taken on the line IX—IX of Fig. 7, and Fig. 10 is a plan view of one of my cutting tools which however may be made of different lengths as desired for the work intended and the angularity of the point may also be varied depending upon the characters of the materials to be cut.

Referring now to the various characters of reference on the drawings:—

1 is the roof of the mine which sometimes is of slate, shale, sandstone, or other material, 20 2 is the floor of the mine which may be composed of different or similar minerals, 3 is a layer of shale or bone coal and on top of the purer coal which is a mixture of coal with other noncombustible materials, containing 25 less combustibles than the coal itself and such bone coal or shale may occur either at the top or elsewhere in the coal or in some particular cases it may be practically absent.

4 is the vein or seam of coal in its original 30 position. 5 is the undercut produced therein by the miner using my invention and 6 indicates the side wall of the mine. The beginning portion adjacent to the first opening or sump of the cut is indicated as 7 and the 35 approximate line of the first cut is indicated at 8. After the coal is cut approximately to the line 8, another and longer tool may be used to cut it to a greater depth as desired before wedging or blasting it down.

40 The wheeled support or carriage is generally indicated as 9, and 10 is the central portion of the axle thereof. 11 are the end or bearing portions of the axles, 12 are the wheels mounted on the axles provided with 45 the washers 13 and cotter pins 14 which are inserted in the holes 15, the axles being provided with annular flanges 16 to form an inner support or abutment for the wheel hubs. The frame portion of the wheeled 50 support is indicated as 17 which preferably consists of thin metal plates of sufficient strength but of light weight and in fact the entire wheeled support and other parts of the apparatus are made as light as possible 55 to facilitate ease of operation. 18 is the lower curved portion of the socket or support for the pickhammer, 19 is the beaded or reinforcing on the edge thereof. 20 is a hinge connecting the lower portion of the 60 socket member 18 with the upper or movable portion thereof indicated as 21 while 22 is a rearwardly projecting portion of the socket cover provided with the opening or notch 23. 24 is a bearing lug attached to or 65 formed integral with the upper portion of

the cover having the slot 25 therein adapted to receive the hinged eyebolt 26 whereby the cover 21 is secured in operative position by means of the thumb nut 27. 28 is a pickhammer the hammer portion of which is adapted to be reciprocated several hundred times per minute by compressed air or otherwise. 29 is a flange on the pickhammer adapted to abut the rear end of the socket and thus assist in holding the parts in proper relative position. 30 is a split collar secured to the forward end of the pickhammer for a similar purpose, being provided with the bolt 31 in order to clamp or adjust it in position by means of the nut 32.

33 is a cotter pin which is inserted through a hole in the threaded end of the bolt 31 and below the nut 32 in order to insure that the nut will not become loose and this cotter pin is provided with a chain keeper 34, one end of which is secured by means of the link 35 to the outer end of the collar 30 to prevent its loss.

My mining tool is indicated at 36 preferably having a round or octagon shaped shank or body portion having a square inner end, the outer working end being provided with a point portion which may be inclined from the body portion at various angles as before stated but I have found it will operate best for certain kinds of coal if this angle is approximately 15 degrees.

The handles of the apparatus are indicated at 37 and these are adapted to be grasped by the miner and air under pressure is supplied to the pickhammer through the hose 38 and its connections. A roll or projection in the floor of the mine is indicated at 39 in order to illustrate such a formation for the reason that the large and massive tools previously mentioned cannot operate over or through such a roll which is composed of solid or various forms of rock, whereas my tool can easily work over or around such rolls or projections.

My apparatus may be operated upon the floor of the mine in case this is smooth enough and the operator can also sit or squat thereon, but sometimes, due to irregularities of the bottom, a plank or plurality of planks secured together by cleats nailed thereto will serve as a proper and smooth support for the apparatus and the same or a similar board seat may be used by the miner. A portion of such a plank for supporting the apparatus is indicated in section as 40 in Fig. 4.

The pickhammer may be of various forms similar to those which are used for drilling and cutting rock, minerals or other substances and preferably operated by air although it may be operated electrically or otherwise and it is also rotatable in the socket 18 and it may be removed or replaced therein by the operation of the upper portion or

closure 21 thereof and its appurtenances previously described.

The construction of the pickhammer is such that the mining tool 36 is not rotated 5 between its successive strokes and its position and operation is therefore determined by the miner in order to produce the results which he desires.

Having thus described the apparatus I 10 will now briefly explain its operation:—Although I have shown my mining tool in connection with what is known as a pickhammer, other forms of apparatus capable of producing a powerful reciprocating action may also 15 be used, but I will continue the use of the word "pickhammer" for the sake of simplicity of description.

The apparatus being in position illustrated in Figs. 1 and 2 and adjacent to the face of 20 the coal the cross handles of the pickhammer are grasped by the operator and he begins by placing the apparatus in position, and then admits air to the pickhammer thus reciprocating the tool 36 several hundred strokes 25 per minute and he so manipulates it as to cut the sump or triangular shaped opening illustrated in Fig. 2 in the face of the coal. He then continues the punching and shearing 30 of the coal until he has traversed the length of the cut intended and while this is continuing an attendant or helper shovels away the cut coal so that the miner can see and better direct his work.

As this is being done the apparatus is so 35 operated that the inclined point of the tool 36 penetrates into the massive coal in place and also shears off portions sidewise due to the penetrating action of the point and the powerful lateral component of the pressure 40 thereby produced on the side of the inclined point portion, thus forcing the fragments sidewise into the openings.

The first part of the cut is preferably made with a shorter tool and a second cut 45 is thereafter made with a longer tool and after these cuts are made the coal is blasted or otherwise forced down into the opening or cut, in the usual manner, after which it is loaded in mine cars, transported to the 50 coal tipple and dumped, whereupon the working face of the coal seam is ready for a repetition of this operation.

Although the cut in the coal seam is illustrated at the bottom thereof, my apparatus 55 will cut it at the top, the sides or elsewhere as will be readily understood.

I have made and used many forms of tools as hereinbefore stated but now prefer to use the style illustrated, as the combined penetrating and lateral shearing effect of the inclined point portion produces excellent results.

The lateral shearing action is due to the 60 inclination of the point portion of the tool 65 which portion also has sufficient side bearing

surface so that it does not crush the coal on the side supported by the main body of the seam so that the weaker and unsupported side must yield and be broken from the mass into the opening, with results of efficiently 70 producing the cut desired.

Although I have described and illustrated my invention in considerable detail I do not wish to be limited to the exact specific details thereof as shown and described, but may use 75 such modifications in, substitutions for, or equivalents thereof, as are embraced within the scope of my invention, or as pointed out in the claims.

Having thus described my invention, what 80 I claim and desire to secure by Letters Patent is:—

1. In a mining apparatus, the combination with an axle and a pair of wheels turnable thereon, of a pickhammer supporting socket carried by the axle and comprising a lower curved half socket and an upper curved half socket hinged on the lower curved half socket, a pickhammer supported in the socket, a flange on the pickhammer in rear of the 90 socket, a split-collar on the forward end of the pickhammer in front of the socket, and means to secure the split-collar in position.

2. In a mining apparatus, the combination with an axle and a pair of wheels turnable thereon, of a pickhammer supporting socket comprising a lower semi-tubular member carried by the axle and a semi-tubular member hinged on the lower member, the upper member having a front end projecting beyond the lower member and having a forwardly extending notch in its rear end.

In witness whereof I hereunto affix my signature.
